TOOL FOR INSTALLING WELL PIPE
PROTECTOR

Charles H. Collett, 4116 Riverside Drive, Burbank, Calif.

Filed Dec. 1, 1958, Ser. No. 777,471

8 Claims. (Cl. 29—267)

This invention relates generally to improvements in tools for tensioning about well drill pipe, protectors of the split collar type comprising a rubber circular body split along one side and desirably containing metal reinforcement extending to or approaching the sides of the split for engagement by a tensioning tool and accommodation of locking means to secure the collar in its tensioned condition.

This split collar type of protector has the advantage of being capable of lateral, as distinguished from endwise slip-over, application to the pipe, with attendant facility and speed in the operations of applying and removing the protector, providing the applicator tool is capable of quick and easy manipulation and is otherwise practicable for association with the collar for both tensioning and releasing of the collar.

My general object is to provide an applicator tool answering to these requirements by virtue of its simple and practical construction, and the facility with which it may be hand manipulated to apply great stresses required for tensioning of the collar.

Structurally, the invention contemplates forming the tool with few, strongly constructed parts comprising the general combination of a body carrying a pair of collar-engaging jaws, and handles operatively associated with the jaws to a degree of mechanical advantage such that manual manipulation of the handles by a single operator can transmit through the jaws very great tensioning forces to the protector collar. In achieving such force transmission, the handles are adapted to actuate cam means acting to produce relative movement together of the jaw terminals at great mechanical advantage achieved by long handle leverage exerted against relatively very short leverage transmitted through the cam means, all to the end that a single operator may quickly and easily bring the protector sleeve to that high degree of tension required for locking or unlocking it about the pipe.

The invention has various additional and specific features and objects such as the novel form and arrangement of the jaws within the body structure, the contact and leverage relation between the jaws and cam surface on the inner ends of the handles, and the provision of means for adjustably varying the range of the cam action, all of which will be understood to better advantage without necessity for further preliminary discussion, from the following detailed description of the accompanying drawing illustrative of a preferred although typical embodiment of the invention, and in which:

FIG. 1 is a plan view showing the tool applied to a protector collar to be tensioned about the drill pipe;

FIG. 2 is an enlarged view similar to FIG. 1, with the top section of the tool body removed and the jaw actuating handles expanded to bring the jaws to the position at which the protective collar is locked in tensioned condition;

FIG. 3 is an enlarged cross-section on line 3—3 of FIG. 1; and

FIG. 4 is an enlarged fragmentary section taken on line 4—4 of FIG. 1.

In the drawings I have shown as an illustrative split sleeve protector, a structure comprising a generally cylindrical rubber body 10 internally reinforced by a metallic band 11 which may also carry projections (not shown) for engaging and gripping the drill pipe 12, the band being embedded in the rubber body and having terminal

2

loops 13 and 14 within interfitting hinge-like projections forming the sides of the collar at the split or gap 15. The band 11 is shown to carry near the terminal loops, riveted-on welded metal cleats 16 engageable by the later described tool jaws inserted within openings 17 in the rubber body to constrict the collar to the FIG. 2 position and bring loops 13 and 14 into alignment for reception of a locking pin 18.

The applicator tool, generally indicated at 20, is shown to comprise a body 21 formed of spaced plates 22 and 23 receiving between them the jaws 24 and the jaw operating handles 25. Each jaw 24 may be formed with a polygonal cross-section shank 26 pivoted to the body by bolts or similar pins 27 extending through the plates 22 and 23 positioned near the outer side of the body relative to the projector sleeve. The jaws have integral tapered portions 28 projecting from the opposite side of the body and having appropriate terminal configurations, such as the reduced diameter tips 29, for engagement with the cleats 14. As will be apparent, the jaws are capable of swinging movement relatively together and apart in their cooperation with the protector collar.

Handles 25 are pivoted by pins or bolts 30 and 31 terminating in the plates 22 and 23 at the outer sides of the jaws 24 and at locations near the sides of the body nearest the protector sleeve. The handles have long extents beyond the pivots 30 and 31, comprising inner lengths 33 which may be brought into substantial parallelism in the FIG. 1 position, and outer angular lengths 34 which cross in the corresponding position, as illustrated. The inner end faces of the handles are cam surfaces 35 adapted to bear against the sides of the jaw shanks 26 and having such curvature as will swing the jaw terminals relatively together as the handles are swung from the FIG. 1 to the FIG. 2 positions. The leverages or radial distances of the cam surfaces 35 from the axial centers of the pins 30 and 31 are very short in relation to the long extents of the handles beyond the pivots, so that jaw converging force applied to the handles in fully spreading them is transmitted at very great mechanical advantage to the jaw surfaces. Consequently, manual actuation of the handles by a single operator can produce very great forces acting to converge the jaws from the FIG. 1 condition to the band constricted and locked condition of FIG. 2.

It will be observed that between their FIG. 1 and FIG. 2 positions, the handles may be swung from one side of the common axial plane P—P' of the pins 30 and 31 into alignment with or somewhat beyond that plane, to limiting positions arrested by engagement of inner portions of the handles with stop pins 36. In the FIG. 1 position of the handles, their inner extents 33 may engage against the outer sides of the jaw shanks 26, where stop pins 36 are received within recesses 37 in the handles.

55 To provide for exactness in the terminal approaches of the jaws in their fully converged position of FIG. 2, provision is made for varying the effective range or throw of at least one of the cams 35. For this purpose, pin 31 is shown to carry an integral eccentric enlargement or sleeve 38 which is rotatably adjustable within opening 39 in the corresponding handle to vary the jaw displacing range of the associated cam, the eccentric being held, after adjustment, in fixed position by tightening nut 40.

If desired, the body plates 22 and 23 may be additionally held together by a bolt 42 extending centrally through the plates.

The tool 20 has such lightweight and convenient portability as to permit its quick and easy application to the protector sleeve in the FIG. 1 condition. With the jaw terminals 29 thus engaged against the cleats 14, the handles may be spread outwardly to the fully opened positions of FIG. 2 in which the jaw terminals 24 have become

cammed relatively together to the extent required for tensioning of the protector sleeve and bringing of loops 13 and 14 into alinement to receive the locking pin 18. When the protector sleeve is to be removed from the pipe, the tool is similarly manipulated to relieve the loop pull on the pin 18 and thus permit removal of the pin and restoration of the protector collar to untensioned condition.

I claim:

1. A tool for tensioning about well drill pipe a flexible split protector collar, comprising a supporting member, a pair of jaws having terminals projecting from one side of said member for engagement with the protector collar at opposite sides of its split, a pair of elongated jaw actuating handles pivoted to said member and swingable apart from positions beyond the side of said member opposite its first mentioned side to spread positions in which the inner end extents of the handles come substantially into longitudinal alignment, means pivotally mounting the jaws to said member for relative lateral movement together of their collar-engageable terminals to predetermined inner-most collar tensioning positions, and said jaws and handles having interengageable portions actuatable by swinging movements of the handles to move the jaw terminals relatively together to said innermost collar tensioning positions when the handles are swung to said spread positions at which their inner extents are substantially aligned.

2. A tool according to claim 1, in which the jaws are substantially straight and said jaw terminals have substantially cylindrical ends.

3. A tool according to claim 1, in which said inner end extents of the handles are swingable into a common plane of alignment and then beyond that plane.

4. A tool according to claim 1, in which the jaw-engaging portions of the handles are cam surfaces on the handles.

5. A tool for tensioning about well drill pipe a flexible split protector collar, comprising a body including a pair

of spaced plates, a pair of jaws carried between said plates and having terminals projecting from one side thereof for engagement with the protector collar at opposite sides of its split, pivots mounting the jaws for movement of their terminals together and apart, a pair of elongated jaw actuating handles extending from between said plates at the outsides of said jaws and swingable apart from positions at the side of the body opposite its first-mentioned side, pivots nearer said terminals of said jaws than the first-mentioned pivots for mounting the handles for swinging movement, and cam surfaces on the inner ends of the handles engageable with the sides of the jaws at locations between their pivots and terminals to move said terminals together for tensioning of the protector collar about the pipe.

10 6. A tool according to claim 5, in which the inner extents of the handles are swingable from jaw expanded positions at one side of the common axial plane of the handle pivots to a jaw converged position at the opposite side of said plane.

20 7. A tool according to claim 6, in which the outer portions of the handles extend generally parallel and then convergently from the body so that the handles may be swung to crossed positions.

25 8. A tool according to claim 5, including also eccentric means associated with one of the handle pivots and adjustable to vary the effective jaw displacement by the cam by the corresponding handle.
